123,706

DESIGN FOR A COMBINATION PEN STAFF AND NIB THEREFOR

John Van Dine, Fair Lawn, N. J.

Application April 12, 1939, Serial No. 84,239

Term of patent 3½ years

To all whom it may concern:

Be it known that I, John Van Dine, a citizen of the United States, residing at Fair Lawn, in the county of Bergen and State of New Jersey, have invented a new, original, and ornamental Design for a Combination Pen Staff and Nib Therefor, of which the following is a specification, reference being had to the accompanying drawing, forming part thereof.

Fig. 1 is a front elevational view of a combination pen staff and nib therefor, showing my new design.

Fig. 2 is a fragmentary view of the staff shown in broken lines, and an enlarged view of the pen.

Fig. 3 is an end view looking at the same from the lower end of Fig. 1.

The essential features of the design reside in the part shown in full lines.

I claim:

The ornamental design for a combination pen staff and nib therefor, substantially as shown and described.

JOHN VAN DINE.
